UNITED STATES PATENT OFFICE.

CHARLES T. GRAHAM, OF GRAND RAPIDS, MICHIGAN, ASSIGNOR TO AMERICAN PARLOR FRAME COMPANY, OF SHEBOYGAN, WISCONSIN, A CORPORATION OF WISCONSIN.

DESIGN FOR A SETTEE FRAME OR SIMILAR ARTICLE.

Application filed May 28, 1928. Serial No. 26 883. Term of patent 3½ years.

To all whom it may concern:

Be it known that I, CHARLES T. GRAHAM, a citizen of the United States, residing at Grand Rapids, in the county of Kent and State of Michigan, have invented a new and original and ornamental Design for a Settee Frame or Similar Article, of which the following is a specification, reference being had to the accompanying drawing, forming a part thereof.

The figure is a perspective view of a settee frame, showing my new design. Only a portion of the ornamentation is visible from the illustration, it being understood that this ornamentation is continued around the lower end portions of the frame.

I claim:

The ornamental design for a settee frame or similar article as shown and described.

In witness whereof, I hereunto subscribe my name this 30th day of April, 1928.

CHAS. T. GRAHAM.
